WIRE CONNECTOR

Carroll H. Walsh, Pine Bluff, Ark.

Application February 23, 1950, Serial No. 145,653

5 Claims. (Cl. 24—125)

1

This invention relates to improvements in electrical connectors of the split or bifurcated bolt type, this type of connector being now quite commonly used for electrically connecting conductors or wires.

Connectors as above-designated include generally a head with a pair of parallel and segmentally threaded legs extended therefrom in spaced relation to provide a wire receiving space or slot therebetween, a nut threadedly engaged with the legs, and a spacer movable with the nut for maintaining the parallel relationship of the legs when the nut is tightened against conductors disposed in the slot.

Because of the necessity that the spacer slide freely to enable the nut to be readily tightened, together with the fact that some tolerance is necessary between the threads of the nut and the threaded legs for commercial manufacture, presently available split bolt connectors are easily damaged by deformation of the body when tightened to lock the conductors in good electrical connection. Such deformation usually results in damage to the threads of the segmentally threaded legs, so that the connector cannot be reused if it can be removed from the conductors, and the latter operation may be very difficult, or impossible without such damage to the connector as to preclude its further use.

It is the prime object of the present invention to provide a connector of the split bolt type in which the movements of the elements resulting from the tightening of the nut thereof to fasten the conductors in the slot will resist the undesired deformation heretofore mentioned. Such a construction will provide a connector capable of normally great clamping strength for holding the conductors in connection, and a connector having high reusability, and it is an object of the present invention to provide such a connector.

With this and such other objects and advantages in view as may appear in the description to follow, my invention resides in the novel shape and arrangement of the cooperating parts which constitute the connector, a preferred embodiment of which is shown by the accompanying drawing, in which:

Fig. 1 is an elevation of the connector, as employed for connecting a pair of laterally adjacent conductors; Fig. 2 is a view of the connector taken along the line 2—2 of Fig. 1, and shown partly in section; Fig. 3 is a section taken along the line 3—3 of Fig. 2; Fig. 4 is a sectional view illustrating the device when untightened; and Fig. 5 is a section along the line 5—5 of Fig. 4.

2

Referring now by characters of reference to the drawing, at 10 is indicated a substantially U-shaped member forming the body of the connector, which has the parallel legs 11 of segmental cross section, the legs being exteriorly threaded. An interiorly threaded nut 18 threadedly engages the legs 11, and rotatably supports the spacer 12. The central portion of the spacer 12 has a width slightly less than the bore of the nut 18, and is free to move in the space between the legs 11. At its upper end, the spacer 12 (Fig. 4) is provided with the portion 15 extended outwardly over the nut 18, and at its lower end, with the portions 16 outwardly bent under the nut 18, the spacer and nut being thus fastened together and removable from the U-shaped member 10 as a unitary structure.

The parallel inner sides of the legs 11 are provided with a row of longitudinally extending alternate grooves and ridges 14, arranged to register, when the nut 18 is untightened, with the similar grooves and ridges 13 formed on the opposing sides of the spacer 12, as shown in Fig. 5. In addition, the arcuate groove 17, V-shape in section and eccentric with respect to the bore of the nut 18, extends upwardly into the lower surface of the portion 15 of the spacer 12. When the nut 18 is untightened, the upwardly and coaxially extending ridge 19 around the upper surface of the nut 18, extends only slightly into the eccentric groove 17.

Assuming that the elements of the device were in the unstressed positions shown in Figs. 4 and 5, and that the nut 18 has subsequently been rotated to firmly clamp the conductors 20 between the head of the U-bolt 10 and the spacer 12, the elements of the device are found to have taken the positions shown in Figs. 2 and 3. In so doing, the V-shaped circular ridge 19 has further entered the V-shaped eccentric groove 17, thereby moving the spacer 12 laterally along the sloped surfaces of the grooves 14 on the inner sides of the legs 11. The lateral movement of the spacer 12 is caused by the camming action resulting from the initial non-coaxial engagement of the ridge 19 of the nut 18 with the groove 17 of the spacer 12. After the spacer 12 has been moved endwise by turning the nut 18 until the conductors 20 are clamped together, continuation of the turning of the nut 18 in the same direction causes the right-hand surface of the ridge 19 to further slide along the right-hand surface of the groove 17, as viewed in Fig. 4, thus forcing the spacer 12 to move to the right. In so doing, the spacer 12 in turn must slide along the right-hand surfaces of the origi-

nally respectively aligned ridges 13 of the spacer 12 and the grooves 14 on the inner sides of the legs 11. The latter movement of the spacer 12 forces the legs 11 apart, as may be necessary to assure full thread engagement of the cooperating threads on the outer surfaces of the legs 11 and the nut 18, and effectively resists any tendency to deform such threads because of the necessary manufacturing tolerance between these members.

I have found that connectors built in accordance with my invention herein will permit an increase of 30% more inch-pounds to be applied to the nut in tightening than is possible with connectors not having the improvements herein described, with the same reusability of the connectors. In addition, the construction herein, because of the application of favorably directed stresses of higher magnitude, is much less susceptible to loosening from vibration of the conductors in service position.

Although the invention has herein been described in considerable detail, it is to be understood that such description is intended as illustrative rather than limiting, as the invention may be variously embodied.

I claim:

1. In a wire connector of the split-bolt type having a bifurcated bolt providing a wire receiving slot opening out through one end and forming two segmentally and exteriorly threaded legs the inner surfaces of which extend in substantially parallel relationship, a nut threaded upon the legs of said bolt over the slot thereof, and a spacer positioned in the orifice of the nut for rotation about the axis of the orifice and formed to slide along the slot as the nut is rotated therealong, means including integral portions of said spacer which extend outwardly over the upper surface of said nut for fastening said spacer to said nut, arcuate grooves eccentric with respect to said nut extending upwardly into said portions from the lower surface thereof, a circular ridge formed on the upper surface of said nut concentric therewith and disposed in alignment with one side only of each of said arcuate grooves and to enter said grooves in alignment therewith only in response to lateral shift of said spacer, a row of parallel and longitudinally extending grooves formed in the inner surfaces of said legs and a row of matching ridges formed on the opposing outer surfaces of said spacer normally aligned with said grooves, said circular ridge aligning with said matching ridges moving laterally to misalignment with the associated grooves when said nut is tightened to engage said spacer with conductors positioned in said slot.

2. The combination with a wire connector of the split-bolt type having a bifurcated bolt providing a wire receiving slot opening out through one end and forming two segmentally and exteriorly threaded legs the inner surfaces of which extend in a substantially parallel relationship, a nut threaded upon the legs of said bolt over the slot thereof, and a spacer anchored in the orifice and formed to slide along the slot as the nut is rotated therealong, of means including integral portions of said spacer for anchoring said nut thereto, arcuate grooves eccentric with respect to said nut extending upwardly into said portions from the lower surface thereof, a circular ridge formed on the upper surface of said nut concentric therewith and disposed to align with one side only of each of said arcuate grooves and to enter said grooves in alignment therewith only

in response to lateral shift of said spacer, a row of parallel and longitudinally extending grooves formed in the inner surfaces of said legs and a row of matching ridges formed on the opposing outer surfaces of said spacer normally aligned with said grooves, said circular ridge moving into said arcuate grooves and causing said matching ridges to move sidewise to misalignment with the associated grooves when said spacer is restrained against longitudinal motion and said nut is tightened thereagainst.

3. The combination with a wire connector of the split-bolt type having a bifurcated bolt providing a wire receiving slot opening out through one end and forming two segmentally and exteriorly threaded legs the inner surfaces of which extend in substantially parallel relationship, a nut threaded upon the legs of said bolt over the slot thereof, and a spacer fastened in the orifice of the nut for rotation about the axis of the orifice and formed to slide along the slot as the nut is rotated therealong, of means including integral portions of said spacer which extend outwardly over the upper surface of said nut for fastening said spacer thereto, arcuate grooves of inverted V-shape eccentric with respect to said nut extending upwardly into said portions from the lower surface thereof, a circular inverted V-shaped ridge formed on the upper surface of said nut concentric therewith and disposed to align with a portion of one side only of each of said arcuate grooves and to enter said grooves in alignment therewith only in response to lateral shift of said spacer, a row of parallel and longitudinally extending V-shaped grooves formed in the inner surfaces of said legs and a row of matching ridges formed on the opposing outer surfaces of said spacer normally registering with said grooves, said circular ridge aligning with said arcuate grooves and said matching ridges moving laterally to misalignment with the associated grooves when said nut is tightened to engage said spacer with conductors in said slot.

4. The combination with a wire connector of the split-bolt type having a bifurcated bolt providing a conductor-receiving slot opening out through one end and forming two segmentally and exteriorly threaded legs the inner surfaces of which extend in substantially parallel relationship, a nut threaded upon the legs of said bolt over the slot thereof, and a spacer fastened in the orifice of the nut for rotation about the axis of the orifice and formed to slide along the slot as the nut is rotated therealong, of means including integral portions of said spacer which extend outwardly over the upper surface of said nut for fastening said spacer thereto, arcuate grooves of inverted V-shape eccentric with respect to said nut extending upwardly into said portions from the lower surface thereof, a circular inverted V-shaped ridge formed on the upper surface of said nut concentric therewith and disposed to align with a portion of one side only of each of said arcuate grooves and to enter said grooves in alignment therewith only in response to lateral shift of said spacer, a row of parallel and longitudinally extending V-shaped grooves formed in the inner surface of at least one of said legs and a row of matching ridges formed on the adjacent surface of said spacer and normally registering with said grooves, said circular ridge moving inwardly into said arcuate grooves and causing said matching ridges to move laterally out of registration with said longitudinal

grooves when said nut is tightened to engage said spacer with conductors in said slot.

5. In a wire connector of the split-bolt type, a nut threaded exteriorly over the slot of said bolt, a spacer rotatably mounted on said nut for movement along said slot with said nut, said spacer having outwardly extending portions extended over the upper surface of said nut, mutually engageable sloping surfaces formed respectively along the lower surfaces of said outwardly extending portions and along the upper surface of said nut, said nut cooperating with said spacer

10

to urge said spacer laterally through engagement of the respective sloping surfaces when said spacer is restrained from endwise movement along said slot, and mutually engageable sloped surfaces formed respectively along the inner surface of said slot and the adjacent surface of said spacer, said last-named surfaces engaging in pressure relationship in response to the lateral movement of said spacer.
